UNITED STATES PATENT OFFICE.

WILLIAM D. GHARKY, OF PHILADELPHIA, PENNSYLVANIA, ASSIGNOR TO
THE SUN ELECTRIC MANUFACTURING COMPANY, OF NEW JERSEY.

DESIGN FOR A TELEPHONE-STANDARD.

SPECIFICATION forming part of Design No. 32,527, dated April 17, 1900.

Application filed February 24, 1899. Serial No. 706,738. Term of patent 14 years.

To all whom it may concern:

Be it known that I, WILLIAM D. GHARKY, a citizen of the United States, residing at Philadelphia, in the county of Philadelphia and State of Pennsylvania, have invented 5 and produced a new and original Design for Telephone-Standards, of which the following is a specification, reference being had to the accompanying drawings, forming part thereof.

Figure 1 is a front view of a telephone-standard, showing my new design. Fig. 2 is a side view thereof.

As shown in the drawings, the leading or material feature of my design, which embraces 15 that part of a telephone instrument known as the "standard" or "support" for a desk set and which includes the switch-hook mounting, consists of the cylindrical enlargement A, forming an integral portion of the support B.

This standard or support B is a column flared 20 in graceful curves, approximating an ogee at its lower end b, and reduced through gentle undulations from thence to its upper end at b', where it is joined to the cylinder A, as

shown. This cylinder is horizontally placed 25 with reference to the standard B and has a plane front. Rising from its upper portion are the extension-pieces a, having curved outer surfaces which merge at the base into the curves of the cylinder, as shown. The 30 leading features of my new design consist, therefore, of the flaring base b, the column B, tapering gracefully through gentle undulations approximating an ogee curve, and a cylinder A, surmounted by the extension-pieces a. 35

The effect I seek to attain is the general effect of the standard and mounting, the most material part of this being due to the location and shape of the cylindrical part A.

Having described my invention, what I 40 claim as new, and desire to secure by Letters Patent, is—

The design for a telephone-standard as herein shown and described.

WILLIAM D. GHARKY.
